UNITED STATES PATENT OFFICE.

JONAS L. KNOLL, OF LEBANON, PENNSYLVANIA.

DESIGN FOR A BICYCLE-FRAME.

SPECIFICATION forming part of Design No. 29,945, dated January 3, 1899.

Application filed December 12, 1898. Serial No. 699,068. Term of patent 14 years.

To all whom it may concern:

Be it known that I, JONAS L. KNOLL, a citizen of the United States, residing at Lebanon, in the county of Lebanon and State of Pennsylvania, have invented and produced a new and original Design for a Bicycle-Frame; and I do hereby declare the following to be a full, clear, and exact description of the same, reference being had to the accompanying drawing, forming a part thereof.

The drawing represents my bicycle-frame in perspective.

The invention relates to what is known as a "lady's bicycle-frame." The leading features of my design consist in the backbone A, in the form of a flat spring-bar slightly arched, having a short bar thereon, the front end of the backbone terminating in a seat-post B, also in the form of a flat spring-bar slightly inclined rearwardly, said post having its rear end in the form of a forked member a, each branch of which is pivoted to the up-

per portion of a three-arm block K. The post B has its lower end secured to the shaft-hanger C, and the portion below the middle 25 of its length is secured to the front reach D. The middle portion of the post B is united to the upper branches of the blocks K by a looped tubing E, and said looped tubing E is united to the under side of the backbone by 30 a looped flat spring-bar F, having its branches bulging outwardly. The post B is also united to the rear portion of the backbone by a flat spring-bar G, arched upwardly.

Having fully described my invention, I 35 claim—

The design for a bicycle-frame as herein shown and described.

In testimony whereof I affix my signature in presence of two witnesses.

JONAS L. KNOLL.
